DESIGN FOR AN OPHTHALMIC MOUNTING

George E. Nerney, Attleboro, Mass., assignor to
Bay State Optical Company, Attleboro, Mass., a
corporation of Maine

Application February 14, 1933. Serial No. 47,210

Term of patent 14 years

To all whom it may concern:

Be it known that I, GEORGE E. NERNEY, a citizen of the United States, and a resident of Attleboro, in the county of Bristol and State of Massachusetts, have invented a new, original, and ornamental Design for an Ophthalmic Mounting, of which the following is a specification, reference being had to the accompanying drawing forming a part hereof.

In the drawing,

Figure 1 is a top plan view of an ophthalmic mounting showing my new design; and Figures 2, 3, 4 and 5 are fragmentary views in plan, front, rear and perspective respectively, of the endpiece

and the temple at the point of connection on a somewhat enlarged scale.

Dominant characteristics of my design are the sweeping streamline curve of the outer wall of the temple, a continuation of the curve in the endpiece, together with the graceful vertical taper of that portion of the temple adjacent the endpiece.

I claim:

The ornamental design for an ophthalmic mounting as shown and described.

In witness whereof, I have signed my name to this specification this 11th day of February, 1933.

GEORGE E. NERNEY.
